J. A. HEIDBRINK

DEVICE FOR CASTING DENTAL FILLINGS

Filed Nov. 20, 1922

INVENTOR:
JAY A. HEIDBRINK
By Whitley and Ruckman
ATTORNEYS.

UNITED STATES PATENT OFFICE.

JAY A. HEIDBRINK, OF MINNEAPOLIS, MINNESOTA.

DEVICE FOR CASTING DENTAL FILLINGS.

Application filed November 20, 1922. Serial No. 602,149.

To all whom it may concern:

Be it known that I, JAY A. HEIDBRINK, a citizen of the United States, residing at Minneapolis, in the county of Hennepin and 5 State of Minnesota, have invented certain new and useful Improvements in Devices for Casting Dental Fillings, of which the following is a specification.

My invention relates to devices for casting dental fillings. In making dental castings or inlays for use as fillings, it is customary to make a wax model or pattern having the shape of the tooth cavity which is to be filled. The model after being removed from 10 the tooth cavity is surrounded with what is known as investment material with a sprue rod attached to the model and extending outwardly through the investment material, and after this material has become 15 set the wax model is burned out or melted so as to be absorbed by the surrounding material, and the sprue rod having been removed a matrix is thus formed for receiving the molten metal or filling material to 20 form the inlay or casting which is to be placed in the tooth cavity. An object of my invention is to provide a device for causing the molten material to completely fill the matrix so that the casting will have the 25 exact shape of the tooth cavity which it is desired to fill. An object in particular is to provide a device of this character in which the material will be drawn into the matrix by suction exerted below the matrix.

30 The full objects and advantages of my invention will appear in connection with the detailed description, and the novel features embodied in my inventive idea will be particularly pointed out in the claims.

40 In the accompanying drawings which illustrate the application of my invention, Fig. 1 is a top plan view of the device. Fig. 2 is a view in vertical section on the line 2—2 of Fig. 1. Fig. 3 is a side elevational 45 view looking at the right hand side of Fig. 2. Fig. 4 is a view in vertical section on the line 4—4 of Fig. 1. Fig. 5 is a view in horizontal section on the line 5—5 of Fig. 2.

As shown in the drawings, I provide a 50 support which includes a hollow bell-shaped base member 10 which is provided with feet 12. The upper portion of the base member is reduced to form an annular shoulder 14 upon which rests the horizontal supporting member 16 of a clamping device, this horizontal member being resiliently held in place

by a spring 17 engaged by a nut 18 screwed upon a reduced threaded portion 20 above which is a still further reduced threaded portion 22 upon which is screwed the lower 60 end of a flask supporting member 24, the upper end of which is enlarged and provided with an annular flange 26 within which a flask M may be supported. This flask as shown in Fig. 2 contains investment material in which the cavity or matrix C has been formed which is to receive the casting material F. To one end of the horizontal supporting member 16 is pivoted a vertical arm 28 from the upper end of which extends 70 a horizontal clamping member 30 which as shown in Fig. 1 is oval in shape so that the two opposite and longer sides of the oval portion may rest upon the top of the flask. The free end of the clamping member is 75 slotted to receive the upper end of an arm 32 pivoted to the other end of the member 16 from that to which the arm 28 is pivoted. The upper end of the arm 32 is threaded to receive a wing nut 34 which is adapted to be screwed down upon the slotted portion of the clamping member 30. The base 10 and the supporting member 24 are 80 jointly provided with a vertical perforation 36 which extends down into an angularly disposed passageway 38 in the base, this passageway being adapted to connect with a chamber 40. The passage from the chamber 40 to the passageway 38 is controlled by a 85 needle valve 42 having a head 44 by which the needle valve may be turned for adjustment. Connected with the chamber 40 is a horizontal passageway 46 to the outer end of which a nipple 48 is attached. The passage through this nipple is controlled by a 90 shutoff valve 50 and the outer end of the nipple is adapted to receive the end of a flexible tube for conveying compressed air which may be delivered from any suitable 95 source. A passageway 52 connects the perforation 36 with a gauge 54 for indicating the degree of vacuum in this perforation.

100 The operation and advantages of my invention will now be readily understood. A flask M containing investment material I 105 having therein the matrix or cavity C is positioned on the supporting member 24 and clamped thereon as shown in Fig. 2 and the melted filling material is placed at the top of the matrix. The operator then opens the valve 50 which permits compressed air to 110 flow past the needle valve 42 and out of the

downwardly inclined passageway 38, thereby causing suction downward through the perforation 36 and exhausting air from the matrix. The degree of vacuum produced in the perforation 36 may be regulated by turning the needle valve 42 and may be observed on the gauge 54. When the matrix has been completely filled, the valve 50 is turned to shut off the supply of compressed air and upon removal of the flask containing the filled matrix, the device is ready for use with another matrix. The resiliency of the spring 17 permits the clamp to adjust itself to the flasks in case these are not of uniform height. It is desirable that a constant degree of vacuum be maintained during the casting operation, and especially when the matrix is filled by suction exerted on the bottom of the matrix without the application of compressed air to the top thereof. Unless a constant degree of vacuum is maintained until the filling material has chilled and hardened, there will be a tendency for such material to pull up from the bottom of the matrix due to shrinking while becoming chilled. When a vacuum chamber is relied upon to produce the suction, there will be a gradual decrease of the vacuum due to the air drawn from the matrix. In my device, however, in which the suction is produced by a constant and uniform flow of compressed air, the degree of vacuum is maintained constant and this constant degree of vacuum may be regulated or varied as desired by adjusting the needle valve 40. The upward shrinking of the filling material is prevented by thus maintaining constant during the casting operation the degree of vacuum which causes suction to be exerted on the bottom of the matrix.

I claim:

1. A device for casting dental fillings comprising a support adapted to receive a flask containing a matrix to be filled, means for clamping said flask on said support, means for supplying compressed air to the device, means for regulating the pressure of the compressed air which is supplied, and means whereby the escape of compressed air from the device will cause suction to be exerted on the bottom of the matrix.
2. A device for casting dental fillings comprising a support adapted to receive a flask containing a matrix to be filled, means for clamping said flask on said support, means for supplying compressed air to the device, means for regulating the pressure of the compressed air which is supplied, means whereby the escape of compressed air from the device will cause suction to be exerted on the bottom of the matrix, and a gauge for indicating the degree of vacuum produced.
3. A device for casting dental fillings comprising a support adapted to receive a

flask containing a matrix to be filled, means for clamping said flask on said support, said support having a perforation which is underneath the flask when thus positioned and said support having a passage way connecting with the lower portion of said perforation, means for supplying compressed air to said passageway whereby suction will be exerted on the bottom of said matrix through said perforation, and a needle valve in said passageway for regulating the pressure of the compressed air.

4. A device for casting dental fillings comprising a support adapted to receive a flask containing a matrix to be filled, means for clamping said flask on said support, said support having a perforation which is underneath the flask when thus positioned and said support having a passageway connecting with the lower portion of said perforation, means for supplying compressed air to said passageway whereby suction will be exerted on the bottom of said matrix through said perforation, a needle valve in said passageway for regulating the pressure of the compressed air, and a gauge for indicating the degree of vacuum produced.

5. A device for casting dental fillings comprising a base member having a reduced portion toward its upper end, a horizontal clamp supporting member on said reduced portion, a flask supporting member secured to said base member above said clamp supporting member and adapted to receive a flask containing a matrix to be filled, a clamping member pivoted to said clamp supporting member and adapted to engage the upper end of a flask in this position, an arm pivoted to said clamp supporting member, a nut on the upper end of said arm adapted to be screwed down upon said clamping member, said base member and said flask supporting member containing a vertical perforation, said base member containing a downwardly inclined passageway connecting with the lower end of said perforation, and means for supplying compressed air to said passageway whereby suction will be exerted on the bottom of said matrix through said perforation.

6. A device for casting dental fillings comprising a base member having a reduced shouldered portion toward its upper end, a horizontal clamp supporting member on said shouldered portion, a spring engaging the upper surface of said clamp supporting member, a nut on said base member above said shouldered portion engaging said spring and resiliently holding said clamp supporting member in place, a flask supporting member secured to said base member above said nut and adapted to receive a flask containing a matrix to be filled, a clamping member pivoted to said clamp supporting member and adapted to engage

the upper end of a flask when thus positioned, an arm pivoted to said clamp supporting member, a nut on the upper end of said arm adapted to be screwed down upon 5 said clamping member, said base member and said flask supporting member containing a vertical perforation, said base member containing a downwardly inclined passage- way connecting with the lower end of said perforation, and means for supplying compressed air to said passageway whereby suction will be exerted on the bottom of said matrix through said perforation. 10

In testimony whereof I hereunto affix my signature.

JAY A. HEIDBRINK.
